HEATER BASED ON UTILIZATION OF JET PROPULSION UNITS

Bernard Lindenbaum, Dayton, Ohio

Application March 8, 1948, Serial No. 13,735

4 Claims. (Cl. 126—110)

(Granted under the act of March 3, 1883, as amended April 30, 1928; 370 O. G. 757)

1

The invention described herein may be manufactured and used by or for the Government for governmental purposes without payment to me of any royalty thereon.

This invention relates to heating apparatus and particularly to heating units having combustion-operated power means for moving the heat through the system, whereby no external source of power is required for this purpose.

An object of the invention is to provide mechanism in which jet propulsion units are employed to generate both the heat and the power necessary for distributing it.

Another object is to employ a fan or blower for moving the heat through the apparatus and mounting a series of ramjet units at or near the periphery of the fan or blower to coincidentally generate the heat and the power necessary for moving it through the apparatus.

Another object is to provide a heating unit having a fan or blower with ramjet units near the periphery of the blades for simultaneously generating heat and the necessary power for distributing the heat and having also means for maintaining separation of the products of combustion from the usable heated air.

Another object is to provide a heating unit of the character described with a single rotatable element having a series of ramjets for giving it propulsion and means for guiding the products of combustion from the ramjets through a heat exchanger for extracting the usable heat.

Another object is to provide heating apparatus of the character described with a rotating element of relatively large diameter and placing the ramjets near the periphery and placing means nearer the center for moving the usable air through the system with partitioning means for keeping the usable air and the products of combustion separated.

Other objects, advantages, and meritorious features will be readily apparent upon consideration of the description when taken in conjunction with the drawing, wherein:

Fig. 1 is a schematic cross sectional view taken on the line 1—1 of Fig. 2 through a heating unit which embodies my invention in its simplest form and which is applicable for heating airplane engines and like uses where toxic products of combustion may be intermixed with the heated medium without injurious effect.

Fig. 2 is an end view of the heating unit shown in Fig. 1.

Fig. 2a shows the bearing arrangement and the fuel ducts of Fig. 1 to an enlarged scale.

2

Fig. 3 is a schematic view of a slightly more intricate heating unit which embodies my invention and which is applicable for heating buildings, vehicles and like uses where the toxic products of combustion may not be allowed to intermix with the heated medium.

Like reference characters refer to like parts throughout the several views.

The more simple structure shown in Figs. 1, 2, and 2a, may first be described as follows: Concentrically but nonrotatably supported in a cylindrical housing 10 by triple-arm end brackets 12 is a fuel tank 14 of stream-line contour. Tank 14 is constricted intermediate its ends for bearing 15 for a freely rotatable fan 16, the hub of which for purposes of assembly is divided into halves having lugs 17 through which cap screws 21 extend to hold the halves together.

A pair of ramjets 18 are carried on two of the blades of the fan 16 near the outer ends. Ducts 20 supply the ramjets with fuel from the tank 14, a circular row of radial holes 22 being provided through the wall of the tank at the constricted portion and through the fan bearing 15 at 19 for communicating with the ducts 20 in supplying fuel to the ramjets. Seals 24 are provided to prevent fuel leakage between the bearing 15 and the hub of the fan 16. A filler plug 26 is provided for filling the tank 14 with fuel. Leg members 28 support the housing 10 so as to keep it raised off the ground.

The exemplification of my invention shown in Figs. 1, 2a, and 2 is particularly adapted for warming aircraft engines since it requires no outside power source. Moreover, this use of the device does not require that the toxic products of combustion be separated from the heated air which is used in warming the engine.

The ramjets provide both the heat and the power for moving the heated air to the engine which is to be heated. They may be of the self-starting variety or be started by auxiliary power as desired. They are located as far out on the fan blade as possible whereby the relatively high speeds necessary for their proper operation is attained. The fan rotates at sufficiently high speed to insure a continuous supply of fresh air where it is taken in by the ramjets.

It will be seen that the application of the device, Figs. 1 and 2, to the above use is highly appropriate since a relatively low power output for fuel consumed is not a necessary factor, for such portion of the fuel which is not converted to power is converted to heat. Considering the amount of fuel which may be converted to heat,

the apparatus is simple in construction, small in space used and light in weight.

In the somewhat more complex embodiment of my invention shown in Fig. 3, a cylindrical outer casing 30 and a cylindrical inner casing 32 are held in coaxial relation by an annular heat exchanger 34 to which the upper edges of the casings are secured. A circular disc 36 is fitted to the inner diameter of the heat exchanger 34 at its upper end, the outer edge of the disc being 10 welded or similarly secured to the exchanger.

The heat exchanger may be of the tubular-boiler type and comprises a series of vertical tubes 31 having their ends spaced apart both radially and circumferentially in heads 33. The 15 hot gases of chamber 64 pass vertically through the inside of the tubes 31 while the uncontaminated air of the chamber 66 passes upward through the deflectors 45 then horizontally 20 through the spaces 35 between the tubes, thus coming in contact with the heated outside of the tubes.

A tubular member 38 is concentrically positioned with respect to casings 30 and 32 the upper end of the tube being joined, by welding or similar means, to the circular disc 36. The lower end of the tube 38 concentrically supports a bearing cage 40, maintenance of concentricity being assisted by several circumferentially spaced apart radial braces 42 each of which connects the bearing cage 40 to the inner surface 25 of the inner casing 32.

Intermediate the ends of the tube 38 are several circumferentially spaced radial braces 44, the inner ends of which are fastened to the tube 38 and the outer ends to the heat exchanger 34. A series of annular bell-mouthed deflectors 45 are 30 concentrically positioned on the braces 44 and welded or similarly fastened thereto.

A fan 46 has an upwardly extending shaft 48 upon which the inner races of antifriction bearings 50 are spaced by the tubular spacer 52, the outer races of the bearings being push fitted in the bearing cage 40. A nut 54 clamps the two inner races and the spacer together. A short shaft 56 depends from the underside of the fan 45 and is connected by a rotating joint 58 to the fuel supply pipe 60.

A series of ramjets 62 are attached to the blades of the fan 46 and receive their operating fuel through ducts 65 which extend radially through the blades of the fan 46 thereby connecting the ramjets to the fuel supply pipe 60, the ramjets being preferably of the self-starting variety, although auxiliary power may be provided for this purpose if desired. It will be noted that the inner casing 32 is in two parts with the fan 46 extending through the gap between the two parts, the upper part being supported by its attachment to the heat exchanger 34 and the lower part resting on a series of circumferentially spaced radial strips 63, whereby the outer end of the fan which carries the ramjets is confined within the annular combustion chamber 64 while the inner portion of the fan is confined within the cylindrical fresh air chamber 66. A labyrinth seal 68 is provided where the fan passes through the inner casing 32 but this seal may be quite freely fitted since the greater part of the fan is within the inner chamber 66, whereby the pressures are so controlled that any flow of fluid above the fan will always be from the inner fresh air chamber 66 to the outer combustion chamber 64. It is noted that with the arrangement shown there is at all times an abundant supply of fresh air entering the

bottom of the combustion chamber 64 to insure efficient operation of the ramjets.

A filter 70 is supported on the underside of the radial strips 63. An annular plenum 72 of D-shaped cross section surrounds the heat exchanger 34 and is provided with a series of spaced apart distributing pipes 74. A fume collecting cover 76 is attached at its outer edge to the heat exchanger 34 and is provided with a centrally located stack 78 to carry off the toxic products of combustion.

The operation of the heating unit shown in Fig. 3 is substantially as follows:

After the ramjets 62 are started, the rotative speed of the fan 46 may be regulated by any suitable valve means 77 in the fuel supply pipe 60. The outer portions of the blades of the fan 46 which are contained in the annular combustion chamber 64 are preferably so angled as to create only a slight pressure and relatively slow upward movement of the air in the combustion chamber, whereby the hot air gives up the greater portion of its heat as it passes slowly through the heat exchanger 34 into the cover 76 and out the stack 78.

The inner portions of the blades of the fan 46 which are contained in the cylindrical fresh air chamber 66 being so angled as to create a slightly higher pressure in the cylindrical fresh air chamber 66 than in the annular combustion chamber 64, such leakage as may pass through the loosely fitted labyrinth seal 68 will always be from the chamber 66 into the chamber 64.

As the fresh air moves upward in the cylindrical chamber 66 it is turned for radial movement by the deflectors 45 after which it moves radially through the heat exchanger 34 into the plenum 72 from which it is conveyed to the area to be heated by the pipes 74. Thermostatic devices for regulating the heat output by control of fuel admitted to the ramjet, whereby the speed of the ramjet is regulated, or for regulating the output by intermittent operation may be provided.

While in the foregoing description of the heating unit shown in Fig. 3, a hot air type is indicated, it is self evident that the circulating medium may as readily be a liquid in which case the inner portions of the fan may be replaced by the impeller of a pump or a separate liquid pump may be provided.

Various other structural arrangements may be employed without departing from the spirit of the invention, the scope of which is intended to be defined in the appended claims.

I claim:

1. In a heating unit, a cylindrical casing open at the ends, fuel supply means carried within said casing and having a bearing portion, means for holding said fuel supply means in said casing with said bearing portion coaxially positioned therein, a bladed fan rotatable about the axis of said portion, a plurality of ramjets carried on the blades of said fan, said ramjets all being oriented to produce torque in the same direction, said blades having fuel ducts extending from said bearing portion through said blades to said ramjets, and said bearing portion having a passage communicating said supply means with said ducts.

2. In a heating unit, a cylindrical casing open at the ends, a fuel tank carried within said casing and having a bearing portion, brackets holding said fuel tank in said casing with said bearing portion coaxially positioned therein, a bladed fan rotatable about the axis of said bearing portion, a plurality of ramjets carried on the blade of said

75 a

fan, said ramjets all being oriented to produce torque in the same direction, said blades having fuel ducts extending from said bearing portion to said blades to said ramjets, and said bearing portion having a passage communicating said tank with said ducts.

3. In a heating unit, a cylindrical casing open at the ends, a fuel tank of stream-lined contour carried within said casing and having a bearing portion, brackets holding said fuel tank in said casing with said bearing portion coaxially positioned therein, a bladed fan rotatable about the axis of said bearing portion, a plurality of ramjets carried on the blade of said fan, said ramjets all being oriented to produce torque in the same direction, said blades having fuel ducts extending from said bearing portion to said blades to said ramjets, and said bearing portion having a passage communicating with said ducts.

4. In a heating unit, a cylindrical casing open at the ends, a fuel tank of stream-lined contour carried within said casing and having a bearing portion comprising a restriction in said tank intermediate its ends, means for holding said fuel tank in said casing with said bearing portion coaxially positioned therein, a bladed fan rotatable about the axis of said bearing portion and

intermediate the ends of said casing, a plurality of ramjets carried on the blades of said fan, said ramjets all being oriented to produce torque in the same direction, said blades having fuel ducts extending from said bearing portion through said blades to said ramjets, and said bearing portion having a passage communicating said tank with said ducts.
